J. BRIDGE.
SAFETY ATTACHMENT FOR HATCHWAYS.
No. 17,551. Patented June 16, 1857.

UNITED STATES PATENT OFFICE.

JAMES BRIDGE, OF AUGUSTA, MAINE.

SAFETY ATTACHMENT FOR HATCHWAYS.

Specification of Letters Patent No. 17,551, dated June 16, 1857.

To all whom it may concern:

Be it known that I, JAMES BRIDGE, of 5
Augusta, in the county of Kennebec and
State of Maine, have invented a new and
useful Safety Attachment for Hatchways;
and I do hereby declare that the following
is a full, clear, and exact description of the
same, reference being had to annexed draw-
ings, making a part of this specification, in
10 which—

Figure 1, is a vertical section of my im-
provement; (x), (x), Fig. 2, indicating the
plane of section. Fig. 2 is also a vertical
15 section of ditto; the plane of section passing
through the center;—the planes of section
of the two figures crossing each other at
right angles.

This invention relates to a safety attach-
ment to be applied to hatch doors, whereby
20 as the doors are raised guards or fenders
are thrown automatically into proper posi-
tion to effectually prevent persons from ac-
cidentally falling through the hatchway.
The guards or fenders automatically folding
25 against the under sides of the doors as said
doors are closed, so as not to offer any ob-
struction when the hatchway is not in use.

The invention substantially consists in
30 having guards or fenders attached at right
angles to arbors or shafts which are fitted
in bearings or guides attached to the under
sides of the doors near one end. The arbors
or shafts are connected by chains to the
35 flooring and beveled plates are attached to
the under sides of the doors, the plates in
connection with the springs and chain at-
tachments actuating the guards or fenders
as the doors are opened and closed.

To enable those skilled in the art to fully
40 understand and construct my invention I
will proceed to describe it.

A represents a hatchway or the opening
made in the flooring through which goods
or articles are raised and lowered by a tackle
45 in the usual way.

B, B, are the two doors which are ar-
ranged and fitted over the opening A as
usual.

C, C, represent guards or fenders which
50 are attached to arbors or shafts D. The
arbors or shafts D are fitted, one to the
under side of each door B, and work in
guides or bearings (a) (a') the arbors be-

ing allowed to turn in their bearings and
the bearings allowed to slide on the arbors. 55
The arbors D are placed near the ends of
the doors and a chain (b) is attached to the
end of each arbor D the chains being secured
to the flooring. Around each shaft or arbor
D, a spiral spring E is placed. One end of 60
these springs is attached to the guards or
fenders C, as shown at (c) and the opposite
ends bear against the bearing (a'). The
guards or fenders C, C, and arbors may be
constructed of iron and formed in one piece, 65
cast or wrought iron being used. The
guards or fenders project at right angles
from the arbors or shafts and may be
formed each of two parallel bars (d) (d)
as shown in Fig. 1, or they may be arranged 70
or formed in any proper way.

To each door B a plate (e) is attached.
These plates have each a curved or flanch-
lip (f) projecting from it. The edges of
the flanches (f) are of inclined form and 75
are placed near the arbors D, so that the
inner ends of the lower bars (d) of the
guards or fenders will bear against the
edges of the flanches (f).

When the doors B, B, are closed as shown 80
in red Fig. 1 the guards or fenders C will
be against the under sides of the doors.
When the doors are raised the springs E
are compressed, the bearings (a) (a') slid-
ing over the arbors which as the doors are 85
elevated are turned in their bearings by the
inclined edges of the flanches (f) and the
guards or fenders are consequently thrown
outward so as to form a railing or guard,
to the hatchway see Fig. 1. When the doors 90

are closed the guards or fenders are thrown
back against the under sides of the doors
by the springs E.

By this simple device the hatchway when
open will be efficiently guarded, and acci-
dents which now frequently occur will be
avoided. The doors may be retained in
an open position by any proper means, in
the drawings a bar (h) is pivoted to one
end of each door. Said bars having re-
cesses or notches made in them by which
the bars are allowed to catch on pins (i)
driven in one of the beams of the flooring.

I would remark that this device may be
applied to both ends of the doors where nec- 105
essary.

Having thus described my invention, what I claim as new, and desire to secure by Letters-Patent, is:

The guards or fenders C attached to the 5 arbors D which are secured to the under sides of the doors B and connected with the flooring by the chains (b); the above parts

being used in connection with the inclined flanches (f) and springs E, substantially as described, for the purpose set forth.

JAMES BRIDGE.
